UNITED STATES PATENT OFFICE.

MORRIS WISE, OF NEW YORK, N. Y.

HEEL.

SPECIFICATION forming part of Letters Patent No. 487,311, dated December 6, 1892.

Application filed March 10, 1892. Serial No. 424,445. (No model.)

To all whom it may concern:

Be it known that I, MORRIS WISE, a citizen of the United States, residing at New York, in the county and State of New York, have 5 invented new and useful Improvements in Detachable Heels, of which the following is a specification.

This invention relates to an improvement in heels for boots or shoes, said heels being 10 detachable or readily removable and attachable; and the invention consists in certain novel features set forth in the following specification and claims, and illustrated in the annexed drawings, in which—

15 Figure 1 is a side elevation of the heel sectioned along x x , Fig. 2. Fig. 2 is a section along y y , Fig. 1. Fig. 3 is a section along z z , Fig. 1. Fig. 4 is a section along u u , Fig. 3. Fig. 5 is a perspective view of a plate. Fig. 20 6 is a perspective view of a staple. Fig. 7 is a perspective view of a key. Fig. 8 is a side elevation of a modification sectioned along x' x' , Fig. 9. Fig. 9 is a section along y' y' , Fig. 8. Fig. 10 is a section along z' z' , Fig. 8. Fig. 25 11 is a section along u' u' , Fig. 10. Fig. 12 is a perspective view of a plate as applied in Fig. 9. Fig. 13 is a perspective view of a staple as applied in Fig. 9. Fig. 14 is a side elevation of a further modification sectioned along x^2 x^2 , Fig. 15. Fig. 15 is a plan view of Fig. 14. Fig. 16 is a section along y^2 y^2 , Fig. 14.

In the drawings, the letter A indicates the sole to which the heel is to be attached, and B is the heel. The heel is secured to the sole by 35 one or more staples C, having an eye D, and by means of a plate E, having an eye F corresponding to the eye D, a key G being made to interlock the eyes, so as to secure the heel in place. By withdrawing the key or locking 40 device G the heel is free to be removed.

In Figs. 1 to 3 the staples C are shown connected to the sole A and the plate E to the heel B; but manifestly the same result is attained in Figs. 8 to 10, where the staple is 45 connected to the heel, and the plate E to the sole or to the upper or fixed portion of the heel.

By forming the staple C with a suitable head, as seen in Figs. 6 and 13, and inserting 50 the staple in a suitable hole or recess of such size as to prevent the passage of the head,

the staple is held securely in place, but is at the same time free to be removed when the heel is detached, so that when the boot or shoe and the heel are useless or worn the 55 staple C can be readily utilized in another boot or shoe.

The plate E or head of staple C can be readily protected by one or more lifts I, secured to the heel, as in Figs. 1, 8, and 14. 60

To withdraw the key G, any suitable pinchers or tool is employed, the key in Fig. 14 having a shoulder H for the ready engagement of a tool.

In Figs. 14 to 16 the plate E is shown concealed in the sole A or between two thicknesses of sole, and the key G is slid into place along a suitable channel or way M in the sole. When the key is in place, a suitable filling-piece N is made to close the channel, so that 70 the attaching mechanism is concealed, instead of being exposed or partly exposed, as in Figs. 1 or 8, where the key G is seen partly exposed.

The staples C, with their heads, are formed or struck from flat metal and require but narrow slits or openings to allow them to be inserted or removed. Each staple is independent from the other, so that they can be independently removed or inserted, and each staple is made of the desired length to obtain a 80 firm hold. The plate E is also formed from flat metal and is readily bent to form the loop-like projections F, which are formed to correspond to the opening D in the staple, as seen in Fig. 4. 85

What I claim as new, and desire to secure by Letters Patent, is—

1. The combination, with a removable heel, of independently-removable staples C, formed of flat pieces of sheet metal and provided with 90 eyes at one end, a plate E, struck up from sheet metal with a series of loop projections F, corresponding in shape to the eyes in the staples, and a key passing through the loops and eyes, substantially as described. 95

2. The combination, with a sole and a removable heel, each having interlocking eyes, of a key for engaging said eyes, said sole having an interior or concealed channel or way located within the boot or shoe for the key, 100 substantially as described.

3. The combination, with a sole and a re-

movable heel, each having interlocking eyes, of a key for engaging said eyes, said sole having an interior or concealed channel or way located within the boot or shoe for the key, 5 and a filling-piece for said channel or way, substantially as described.

In testimony whereof I have hereunto set

my hand in the presence of two subscribing witnesses.

MORRIS WISE.
